UNITED STATES PATENT OFFICE.

FRIEDRICH OSMER, OF BROOKLYN, NEW YORK.

APPARATUS FOR TAKING OFF AMMONIA FROM BONE-BLACK RETORTS.

SPECIFICATION forming part of Letters Patent No. 287,570, dated October 30, 1883.

Application filed May 22, 1883. (No model.)

To all whom it may concern:

Be it known that I, FRIEDRICH OSMER, of the city of Brooklyn, in the county of Kings and State of New York, have invented a new and useful Apparatus for Taking Off Ammonia from Bone-Black Retorts, of which the following is a specification.

The retorts used for reburning or revivifying bone-black or "char," as it is commonly called, are usually set in an upright position in a furnace, and the char is filled into and piled above the open upper ends of the retorts. As the char is removed from the lower ends of the retorts the char above gravitates down into the retorts, and thus the operation is made continuous. The char contains ammonia in considerable quantities, and as the char settles down into the hotter part of the retort the ammonia is volatilized and passes upward; but it has no avenue of escape save through the pile of the char above the retort, and as the char is comparatively cool at the top of the pile a large proportion of the ammonia-vapor is reabsorbed and does not escape.

The object of my invention is to provide for the free escape of the volatilized ammonia without compelling it to pass through the pile of char, and thereby to render the char better for use in sugar-refining, and to save the ammonia, if it be desired. Commonly a large plate or metal feeding-floor is placed above the open upper ends of a bench of retorts, and from this plate feeding-throats extend downward into the upper ends of the retorts.

My invention consists in the combination, with a char-retort, of a double floor or two floors at the top thereof, affording a space between them, a throat leading downward from the upper floor into the retort, and made smaller in size than the retort, but of corresponding shape, so as to form between it and the retort a flue, which communicates with the space between the two said floors, all as more particularly hereinafter described.

I may provide openings in the feeding-throat, through which ammonia can escape from the char in the throat into the surrounding flue; and these openings are covered by hoods arranged on the interior of the feeding-throat, so that they will not become clogged or stopped with char. At the upper end of the retorts I

arrange a double floor, or two floors, affording between them a clear space for the escape of ammonia, and I extend throats from the lower floor down into the retorts, and feeding-throats of smaller size from the upper floor down into the retorts. The spaces between the outer throats and the inner and smaller feeding-throats then form escape-flues for ammonia. I connect pipes with the space between the floors, to take off the ammonia to a larger pipe or conduit, from which it may be passed to a condenser, or directly into water to absorb it.

All the above-mentioned features of construction and arrangement are included in my invention.

In the accompanying drawings, Figures 1 and 2 are partly sectional elevations in planes at right angles to each other of retorts having my invention applied to them; and Fig. 3 is a horizontal section on the plane of the dotted line *x x*, Fig. 2, looking upward.

Similar letters of reference designate corresponding parts in all the figures.

A designates the retorts, which are of the usual form, and which are heated by a furnace, (Not here shown.) The upper ends of the retorts are open, and at the upper ends is the usual plate, *B*, surmounted by brick-work *B'*, on which is placed the usual plate or floor, *C*. From the plate or floor *C* throats *C'* extend downward into the open upper ends of the retorts, and are of a size to fit snugly therein. These throats *C'* are usually the feeding-throats, through which char is introduced into the retorts, and the upper ends of the retorts are wholly filled by the descending column of char.

In carrying out my invention I place over the ordinary plate or floor, *C*, a second plate or feeding-floor, *D*, which is slightly raised, so as to afford a clear space, *a*, below it; and from this upper plate or floor feeding-throats *D'* extend downward through the throat *C'*, and preferably slightly below them, as shown in Figs. 1 and 2. The feeding-throats *D'* are or may be of the same shape as the outer throats, *C'*, but are of smaller size, so that between them and all around the feeding-throats there is left a space, *a'*, which is kept free from char, and forms a flue for the escape of ammonia. The char is placed or piled on the upper plate or floor, *D*, and passes therefrom down the

throats D' into the retorts A. In the present example of my invention the upper plate or floor, D, has a downwardly-extending flange, b, which forms a closed chamber or space, a, and volatilized ammonia can escape from the flue a' around its whole circumference and into the space or chamber a.

Pipes c conduct the volatilized ammonia from the space or chamber a to a common conduit, E, by which it may be conducted to a condenser or water-tank, to be condensed or absorbed. If desired, the ammonia may be saved and utilized.

Of course the char around the inner surface 15 of the retort is hottest, and the ammonia driven off therefrom can pass directly upward along the wall of the retort and out of the flue a'.

In order to further prevent ammonia from passing upward through the feeding-throats 20 D', I form openings d in the throats D', through which ammonia can escape into the surrounding flue-space a', and I cover these openings with hoods e on the inner walls of the feeding-throat, which prevent the holes from becoming clogged or stopped by char. I prefer to place the holes d at different elevations around the throat, as shown in Fig. 1.

The inner throats, D', may have ribs f, formed on their interior, to maintain the necessary space around the feeding-throats and insure the feeding-throats being placed centrally in the outer throats, C'. By my invention I afford a free passage for the escape of the ammonia without passing it through the pile of char, and it is therefore carried off, and is not again absorbed.

My improved apparatus enables any other noxious matters which may be volatilized by the heat to readily escape without passing 40 through the feeding-throat.

What I claim as my invention, and desire to secure by Letters Patent, is—

1. The combination, with a char-retort, A, of a double floor or two floors, C D, having the space a between them, the feeding-throat D', 45 extending from the floor D downward into the retort, and made smaller in size than the retort, but of corresponding shape, so as to form between it and the retort a flue, a', which communicates with the space a between said floors, substantially as herein described.

2. The combination, with the retort A, of the feeding-throat D', provided with hooded openings d, and the surrounding flue or passage a', with which said openings communicate, substantially as herein described.

3. The combination, with the retort A, of the feeding-throat D', provided with hooded openings d, arranged at different elevations or levels, and the surrounding flue or passage a', 60 with which said openings communicate, substantially as herein described.

4. The combination, with retorts open at the upper ends, of a double floor or two floors forming a space or chamber between them, 65 throats leading from the lower floor into the retorts, and feeding-throats, smaller in size than the first-mentioned throats, extending from the upper floor into the retorts, and forming between themselves and the larger throats the 70 flues or passages a', substantially as herein described.

5. The combination of the retorts A, the floors C D, the latter provided with the flange b, the throats C' D', and the escape-pipes and conduit c E, all substantially as herein described.

FRIEDRICH OSMER.
